CHICKEN SPLITTER

Joseph J. Hannan, Chicago, Ill.

Application September 16, 1938, Serial No. 230,305

3 Claims. (Cl. 146—95)

This invention relates to cutting devices, and more particularly to a cutter adapted for use in cutting or splitting chickens.

An object of this invention is to provide a rotary cutting device in the form of an attachment which may be detachably connected to a power device in the form of a motor, the device being so constructed as to provide a means whereby a dressed chicken may be quickly cut into the desired number and kinds of pieces.

Another object of this invention is to provide a cutter of this kind which is simple in construction and which may be manufactured at a relatively small cost.

15 A further object of this invention is to provide in a rotary cutter of this kind an adjustable guard means on opposite sides of the rotary cutter which not only guide the rotary cutter, but also serve as a gage for gaging the depth of 20 the cut which is being made.

A still further object of this invention is to provide a means for splitting or cutting chickens or like fowl which may be detachably connected to a motor operated meat grinder, the grinder 25 being removed from the motor and the splitting or cutting device being substituted therefor.

Embodying the objects aforesaid, and to others which may directly or indirectly appear, the invention consists of the novel construction, combination and arrangement of parts, as will be more specifically referred to and illustrated in the accompanying drawing, wherein is shown the preferred embodiment of the invention, but it is to be understood that changes, variations and 35 modifications may be resorted to which fall within the scope of the invention as claimed.

In the drawing:

Figure 1 is a detail top plan of a cutting attachment or splitter constructed according to an embodiment of this invention,

40 Figure 2 is a detail side elevation of the device, and

45 Figure 3 is a detail front elevation of the device showing the manner of connecting the device to a motor.

Referring to the drawing, the numeral 10 designates a table or platform which is adapted to be constructed out of a suitable sheet of material such as metal or the like, and which is of a suitable thickness and size. The table or plate 10 has secured to one edge thereof a right angularly disposed plate 11 which may be secured as by screws or bolts 13, and an outwardly extending bearing or boss 12 is carried by the plate 11. The boss 12 is provided on its outer end with a re-

duced cylindrical boss or extension 14 which is adapted to engage in a socket 15 provided in a bearing extension 16 forming part of a motor M. The boss 12 at its outer end is provided with a pair of diametrically disposed keys or lugs 17 which are adapted to engage in key ways or recesses provided in the bearing 16, so that the boss 12 will be held against rotation relative to the boss or extension 16. A screw 18 is threaded through the boss 16, and is adapted to engage 10 the reduced boss or extension 14 so as to hold the boss 14 against longitudinal movement in the socket 15.

A drive shaft 19 is journaled through the bearing or boss 12 and projects outwardly through the reduced boss 14 being provided on the extended end thereof with a square or angular portion 20 which is adapted to seat snugly into a complimentary square or angular socket 21 provided in the outer end of the motor shaft 22. The plate 20 or platform 10 is provided with a second depending plate or flange 23 which is secured to the underside of the plate 10 by means of bolts or screws 24. The shaft 19 extends through the flange or plate 11 and also through the plate or flange 23, and is held against lengthwise movement by means of a nut 25 which is threaded onto the outer end of the shaft 19.

A thrust collar 26 is secured to the shaft 19 adjacent the outer end thereof, and is adapted 30 to engage against the inner side of the plate or flange 23 so that the shaft 19 will be held against lengthwise movement relative to the bearing 12.

A collar 27 is disposed on the shaft 19 at a point substantially centrally below the plate 10 and a disc shaped cutter 28 engages against the collar or flange 27 being tightly held on the shaft 19 against the collar or flange 27 by means of a nut 29 which is threaded onto the shaft 19. The cutter 28 may either be provided with a smooth 40 cutting edge or, if desired, the cutting edge of the cutter 28 may be toothed. The cutter or blade 28 projects upwardly through an elongated slot 30 provided in the platform 10.

The platform 10 is provided on opposite sides 45 of the projecting portion of the cutter or blade 28 with a pair of guards or guide members 31 and 32. The guards or guide members 31 and 32 are provided in the form of a longitudinally curved bar provided with flanged or straight end portions 33 and 34 respectively. These straight end portions comprise base portions which are adapted to engage on the upper surface of the platform 10. The platform 10 on one side of the blade 28 is provided with an elongated slot 35 55

and bolts 36 are adapted to engage through the base or foot members 33 of the guard 31, and the guard 31 is fixed in adjusted position relative to the length of the slot 35 by wing nuts 37 engaging the bolts 36. In the present instance, the wing nuts 37 are positioned on the underside of the platform 10.

The platform 10 is also provided with a second elongated slot 38 and bolts 39 engage through the feet or base members 34 and through the slot 38. A wing nut 40 is threaded onto the lower end of each nut 39 on the side of the blade 28 opposite from the wing nuts 37.

In the use and operation of this attachment, the stub 14 is adapted to be inserted in the socket 15 of the motor bearing 16, and to be secured by means of the set screw 18. The stub 14 is adapted to support the entire attachment from the bearing 16 of the motor M. The inner end of the boss 12 is adapted to abut against the outer end of the boss or bearing 16 of the motor M and the square end 20 of the drive shaft 19 is adapted to snugly engage in the socket 21 of the motor shaft 22. The two guard members 31 and 32 are adjusted longitudinally of the slots 35 and 38 respectively, so that the desired portion of the cutting blade 28 will project forwardly of the guide members 31 and 32 as shown in Figure 2.

The chicken is then engaged with the rotary blade 28 being moved forwardly and upwardly in an arcuate movement along the platform 10 and upwardly along the guard members 31 and 32. The blade 28, which is adapted to rotate at a relatively high speed, will thereby split the desired portion of the chicken as the chicken is passed over the platform and the guard members 31 and 32. This operation will speed up the cutting or splitting of the chicken and in addition will prevent the formation of splinters of bone as the rotary blade 28 will cleanly cut through not only the meat of the chicken, but also the bones.

The attachment hereinbefore disclosed may be mounted on the motor M which forms a part of a meat grinder, the grinder being disengaged from the bearing 16 and the attachment inserted in place of the grinder. This device can be manufactured at relatively a small cost and due to the simplicity thereof the device will not readily get out of order, and can be quickly applied or removed from the motor M by means of the set screw 18.

What I claim is:

1. A device as set forth comprising a table member, a pair of downwardly extending spaced

apart plates carried by said member, a boss carried by one of said plates, a shaft journalled through said boss and the other of said plates, means carried by said shaft and engaging on opposite sides of said other plate to hold said shaft against endwise movement, said table having an elongated slot therethrough and a pair of elongated slots one on each side of said first slot, a disc-shaped blade fixed on said shaft and having a portion thereof projecting through said slot, a pair of guard members carried by said table on opposite sides of said blade, means engaging through said pair of slots adjustably securing said guard on said table, and means carried by said boss engageable with a supporting means for supporting said table in horizontal position while simultaneously coupling said shaft to a driving means.

2. In combination a motor, a boss carried by said motor about the shaft thereof, said boss having a socket concentric to and extending outwardly of said shaft, a table, a shaft rotatably disposed beneath said table, said table having a slot therethrough, a blade fixed to said shaft and projecting through said slot, a guard on each side of said blade, said table having a pair of slots one on each side of said first slots, means engaging through said pair of slots adjustably securing said guards on said table, means carried by said table about said second shaft rotatably supporting said second shaft, and means carried by said latter means engageable in said socket for supporting said table in horizontal position.

3. A chicken splitter attachment for a meat grinder motor comprising a table having an elongated slot therethrough, a pair of plates secured to and depending from said table, an outwardly extending boss carried by one of said plates, a reduced boss carried by said first boss, a shaft journalled through said bosses and the other of said plates, means carried by said shaft engaging on opposite sides of said other plate for holding said shaft against endwise movement, a coupling member carried by said shaft outwardly of said reduced boss, diametrically opposed lugs carried by said first boss engageable with said motor to hold said table in horizontal position, a blade fixed to said shaft and projecting through said slot, said table having a pair of slots one on each side of said first slot and parallel therewith, a pair of arcuate guards disposed one on each side of said blade on the upper side of said table, and means engaging said guards and extending through said pair of slots for adjustably securing said guards on said table.

JOSEPH J. HANNAN.
